(57) **CLAIM**

The ornamental design for a proximal catheter hub body, as shown and described.

DESCRIPTION

FIG. 1 is a perspective view of a proximal catheter hub body, showing our new design;

FIG. 2 is a perspective view of the same design from a different viewing angle;

FIG. 3 is a top plan view thereof;

FIG. 4 is a left side elevation view thereof;

FIG. 5 is a right side elevation view thereof;

FIG. 6 is a bottom plan view thereof;

FIG. 7 is a rear elevation view thereof; and,

FIG. 8 is a front elevation view thereof.

The features shown in broken lines depict environmental subject matter only and form no part of the claimed design.
